(57) **CLAIM**

The ornamental design for a carabiner knife, as shown and described.

DESCRIPTION

FIG. 1 is a left side and bottom perspective view of a carabiner knife with a blade in an extended position, showing my new design;

FIG. 2 is right side and top perspective view thereof;

FIG. 3 is a left side elevational view thereof;

FIG. 4 is a bottom plan view thereof;

FIG. 5 is a right side elevational view thereof;

FIG. 6 is a top plan view thereof;

FIG. 7 is a front elevational view thereof;

FIG. 8 is a rear elevational view thereof;

FIG. 9 is a left side and bottom perspective view of the carabiner knife with the blade in a retracted position;

FIG. 10 is a right side and top perspective view thereof;

FIG. 11 is a left side elevational view thereof;

FIG. 12 is a bottom plan view thereof;

FIG. 13 is a right side elevational view thereof;

FIG. 14 is a top plan view thereof;

FIG. 15 is a front elevational view thereof; and,

FIG. 16 is a rear elevational view thereof.

The broken lines in the drawings illustrate portions of the carabiner knife that form no part of the claim.
